M. S. Branningham.

Portable House.

No 7256.

Patented May 12, 1857.

UNITED STATES PATENT OFFICE.

MATTHIAS F. BRANTINGHAM, OF SANGAMON COUNTY, ILLINOIS.

PORTABLE BARRACK.

Specification of Letters Patent No. 17,256, dated May 12, 1857.

To all whom it may concern:

Be it known that I, MATTHIAS F. BRANTINGHAM, of Sangamon county, State of Illinois, have invented a new Portable Barrack; and I do hereby declare that the following is a full and exact description.
The upright posts A B, C D in Figure 1 are inserted in the ground and the crops of whatever kind are stacked around them 10 until the stacks are as high as desired. No. 1, Fig. 5, an iron ring, is then attached to the upright posts, as shown in Fig. 6, by putting No. 2, Fig. 5, an iron bolt, through the posts A B, C D, as seen in Fig. 6. No. 15 1, Fig. 2, is then hooked in the ring before mentioned as shown, Fig. 6. The rafters, as shown in Fig. 2, Nos. 3 and 4, are put together by tenons and pinned. The framing of the roof being then put together the roof- 20 ing, either boards, thatch, or other suitable materials, is then fastened by hooks, pins, or screws or nails. Fig. 4 represents a brace intended to fit in mortise, as shown in No. 3, Fig. 2, to support the lower portion of the 25 roof. Fig. 3 shows the frame of ends of barrack, being a straight piece of joist or scantling to support the covering of ends.

No. 1, Fig. 3, shows the piece of timber with a mortise. No. 1, shows a button to fasten the ends to brace, Fig. 4, which is easily loosened by moving aside said button. Fig. 5 shows in No. 1 the form of rings to sustain the roof. No. 2 shows the form of bolt or pin to support the ring. No. 3 shows the form of hooks in No. 1, Fig. 2, 35 by which the roof is suspended.

The barrack is so constructed that all the pieces or parts can be taken off separately so that it may easily be removed from place to place. 40

What I claim as my invention and desire to secure by Letters Patent is—

The combination of separate and detached pieces of material as above described, so as to form a barrack as represented in Fig. 1, 45 which can be used for the protection of crops from the weather and which can be readily separated again for removal from place to place and then reconstructed.

MATTHIAS F. BRANTINGHAM.
